(57) **CLAIM**

The ornamental design for a blood pressure measuring apparatus, as shown and described.

DESCRIPTION

FIG. 1 is a perspective view of a blood pressure measuring apparatus in accordance with the design;
FIG. 2 is a front view thereof;
FIG. 3 is a rear view thereof;
FIG. 4 is a left side view thereof;
FIG. 5 is a right side view thereof;
FIG. 6 is a top plan view thereof;
FIG. 7 is a bottom plan view thereof; and,
FIG. 8 is another perspective view thereof.

The broken lines depict portions of the blood pressure measuring apparatus in which the design is embodied that form no part of the claimed design, and the dash-dot-dash lines represent the bounds of the claim and form no part of the claimed design.
